N. C. COTABISH

CONNECTER FOR FIRING EXPLOSIVE CHARGES

Filed Jan. 4, 1921

INVENTOR:

Nelson C. Cotabish
J. Byrnes, Townsend & Brickmire,

ATTORNEYS.

UNITED STATES PATENT OFFICE.

NELSON C. COTABISH, OF CLEVELAND, OHIO, ASSIGNOR TO NATIONAL CARBON COMPANY, INC., A CORPORATION OF NEW YORK.

CONNECTER FOR FIRING EXPLOSIVE CHARGES.

Application filed January 4, 1921. Serial No. 434,971.

To all whom it may concern:

Be it known that I, NELSON C. COTABISH, a citizen of the United States, residing at 13105 Det Ave., Cleveland, in the county of 5 Cuyahoga and State of Ohio, have invented certain new and useful Improvements in Connecters for Firing Explosive Charges, of which the following is a specification.

This invention relates to means for firing 10 explosive charges and more particularly to an improved connector or electrical switch means for connecting a source of current to an electric charge-firing device.

In firing explosive charges, as in mine 15 blasting, for example, the electrical circuits of charge-firing devices have employed a single switch which has, at times, due to closure by faulty construction, carelessness or accident, caused premature explosions.

20 The primary object of this invention is to provide an improved switch means which will more thoroughly safeguard charge-firing circuits and which may readily be coupled to types of electric batteries now on 25 the market.

The above and other objects and the novel 30 features of my invention will be apparent from the following description taken with the accompanying drawings which form a 35 part of this application and in which

Fig. 1 is a view, partly diagrammatic, illustrating a connector embodying my invention and its application in a charge-firing circuit,

35 Fig. 2 is a plan view of the connector on an enlarged scale, and

Fig. 3 is a longitudinal sectional view of one of the connector arms, taken on the line 3—3 of Fig. 2.

40 For purposes of illustration, the invention is herein shown as applied to a well known form of low-tension charge-firing circuit comprising conductors L' and L'' connected to a low-tension detonator or fuse F of any 45 suitable or preferred construction embodying a high resistance wire that may be heated to incandescence by electric current from a suitable battery B. It will be understood that the invention is also applicable to 50 high-tension firing circuits, and other circuits for firing explosives. The flow of current to the fuse or firing device F is controlled by two normally open circuit closers S' and S'', which are arranged within reach 55 of a single person so that they may be simul-

taneously but independently operated by him to fire the charge of explosive.

The normally open circuit closers S' and S'' are arranged as a part of the connector device C by means of which the circuit conductors L' and L'' are electrically connected to the positive and negative binding posts P and N of the battery B. The battery B may be of any suitable type, preferably a multi-cell battery that will give the 60 desired amperage and voltage to fire the fuse. The connector C may be of any suitable type, and as illustrated, comprises two relatively adjustable arms or plates A' and A'' of suitable insulating material such as 65 fiber or other composition adapted to provide rigid supporting means for the circuit closers S' and S'' and associated terminals. The arms A' and A'' may be pivotally connected together at one end, as by a headed 70 bolt D, and may be clamped in various adjusted positions by means of a nut M bearing against the outer side of one arm and having threaded connection with the threaded shank of the bolt D. The free ends of 75 the arm A' and A'' may be provided with suitable metal terminals T' and T'' whereby the connector may be mechanically and electrically coupled to battery terminal posts by the binding screws of the latter. The arms 80 A', A'' also carry suitable binding devices, as spring metal clips K', K'', respectively adapted to connect the wires L', L'' in circuit with the switches S', S'' and terminals T', T''. The terminals T', T''; switches 85 S', S'' and clips K', K'' may be arranged on the adjustable connector arms in any suitable manner, but are desirably arranged in sets, as illustrated.

Inasmuch as the arms A', A'' in this particular arrangement are substantially similar in construction, only the construction of the arm A' will be described in detail.

The terminal T' may consist of a metal plate provided with a notch or recess 10 100 whereby it may be readily applied to a battery terminal post. The terminal T' may be mounted on the arm A' and connected in circuit with the switch S' in any suitable manner, but as shown, is desirably secured 105 in a central slot 11 at the free end of the insulating arm A' by headed screws 12 which are threaded into a metal plate 15 set in the bottom face of the supporting arm. The conducting plate 15 is electrically connected 110

to the terminal T' through the screws 12, and a part of its upper face at one end, as at 151, is exposed in the switch cavity 16 where it is engageable by the free end of the spring metal switch member 17. The switch member 17 is normally open or out of contact with the plate 15 and may be depressed into contact with said plate, as by means of a push button 18 the outer end of which may be exposed at one face of the supporting arm A', but flush therewith to prevent accidental depression of the switch member. The switch member 17 is electrically connected to the terminal clip K', as by a conducting screw 19, which holds the said clip in place on the arm A'. The insulating cover 20 of the switch cavity 16 has a metal bushing 21 set therein to which the fixed end of the switch member 17 is connected, and this bushing may also have threads to receive the threaded end of the screw 19 whereby the cover 20 is held in place. The clip K' may be of any suitable form, and as illustrated, comprises a well known type of sheet metal device having two cooperating hook-shaped parts 22 and 23 to receive and clamp a wire or conductor between them.

The operation and manipulation of the connector will be understood from the foregoing description and from the drawings. The arms A' and A'' of the connector may be spread apart the necessary distance to permit the terminals T' and T'' to be coupled to the binding posts P and N of the battery. The nut M may then be tightened to clamp the arms in this position. Since the switches S' and S'' are independently operable, if either of them is accidentally closed, while the other switch is open, the charge will not be fired. It is necessary to simultaneously depress both circuit closers S' and S'' to fire the charge and it will, therefore, be seen that by the present arrangement, premature explosions due to faulty switch construction or carelessness in operating the same will be greatly reduced.

While I have shown and described a desirable form of my invention in detail, it is to be understood that various changes may be made therein without departing from the spirit of the invention or sacrificing any of the advantages thereof.

I claim:

1. Electrical switch means for use in controlling electrical circuits, said switch means comprising the combination of two independently operable circuit closers, terminals severally electrically connected to said circuit closers and adapted to be secured to the binding posts or terminals of a battery, and means supporting said terminals so they are adjustable relatively to one another.

2. A device for controlling circuits com-

prising, in combination, two normally open independently operable electric circuit closers, relatively adjustable arms, terminals adapted to be electrically connected to said circuit closers and mounted adjacent the ends of said arms and adapted to be electrically and mechanically coupled to the binding posts or terminals of a battery.

3. A device for controlling circuits comprising the combination of two normally open independently operable electric circuit closers, means for supporting said circuit closers whereby one person may operate them simultaneously, and relatively adjustable terminals severally electrically connected to said circuit closers and adapted to be electrically and mechanically coupled to the binding posts or terminals of a battery.

4. A device for controlling circuits comprising the combination of two normally open independently operable electric circuit closers, pivotally connected relatively adjustable arms upon which said circuit closers are mounted so that such circuit closers may be operated simultaneously, terminals adjacent the free ends of said arms and severally electrically connected to said circuit closers and adapted to be electrically and mechanically connected to the binding posts or terminals of a battery.

5. A device for electrically connecting a battery in circuit with means for firing an explosive charge, said device comprising the combination of a pair of pivotally connected arms of insulating material, means for retaining said arms in a predetermined adjusted relation, a terminal mounted at the free end of each arm and respectively adapted to be electrically and mechanically coupled to the binding posts or terminals of a battery, a normally open circuit closer on each of said arms and electrically connected, respectively, to the aforesaid terminals, and means for electrically connecting conductors to said circuit closers.

6. A device for controlling electrical circuits comprising the combination of two normally open independently operable switches, mechanically connected relatively adjustable members upon which said switches are severally mounted, and recessed terminals on said arms severally adapted to be connected to said switches.

7. A connector comprising the combination of two normally open independently operable switches, pivotally connected relatively adjustable insulating arms severally carrying said switches, and recessed metal terminals secured to the free ends of said arms and severally adapted to be connected to said switches.

In testimony whereof, I affix my signature.
NELSON C. COTABISH.
